DIGGING TOOTH

Richard George Holland, 12 Arterial Road,
Killara, New South Wales, Australia

Filed Feb. 13, 1974, Ser. No. 442,263

Claims priority, application Australia Sept. 3, 1973

Term of patent 14 years

Int. Cl. D15—04

U.S. Cl. D39—1 R

FIG. 1

FIG. 4

FIG. 2

FIG. 3

FIG. 1 is a perspective view of a digging tooth showing my new design;

FIG. 2 is a right side elevational view of FIG. 1;

FIG. 3 is a bottom plan view of FIG. 2; and

FIG. 4 is a vertical cross-sectional view taken along the line 4—4 of FIG. 2.

I claim:

The ornamental design for a digging tooth, as shown.
